UNITED STATES PATENT OFFICE

WILLIAM P. BOSTWICK, OF SHORT BEACH, CONNECTICUT

FIGURE TOY

Application filed June 2, 1930. Serial No. 458,974.

This invention relates to toys, and more particularly it pertains to figure toys.

It is an object of the present invention to provide a figure toy especially of the doll 5 type, which may be operated to imitate certain movements or gestures, characteristic of the particular thing of which the toy is an imitation.

It is another object of the invention, so to 10 construct a figure toy of the aforementioned character that it may be grasped by one hand of an operator and by slight pressure exerted upon the limbs of the toy, the same may be caused to perform movements in imitation of the action it is desired to depict.

Other objects of the invention relate to certain novel and improved constructions, arrangements and combinations of parts hereinafter described and particularly pointed 20 out in the claims, the advantages of which will be readily understood and appreciated by those skilled in the art.

The invention will be clearly understood from the accompanying drawing illustrating 25 the invention in its preferred form, and the following detailed description of the construction therein shown.

In the drawings;

Figures 1 and 2 are perspective views 30 respectively showing different positions of the limbs of a figure toy in imitation of a doll, during the operation thereof,

Figure 3 is a longitudinal sectional view taken through the body of the toy,

Figure 4 is a view in front elevation of the body of the toy, the clothes being removed therefrom, and;

Figure 5 is a horizontal sectional view taken on the line 5—5 of Figure 4.

In its present embodiment the invention 40 is illustrated in a figure toy which takes the form of a doll, and in the drawings which form a part of this application, and depict the invention, 10 designates the body of the doll, 11 the head, 12 the arms, and 13 the lower limbs or legs.

The body 10 consists of a back member 14 formed preferably of wood and a curved or lowered portion 15 preferably formed of 50 sheet metal, secured at its ends as at 16 to the

sides of the back member 14. The head 11 has a neck and shoulder portion 17 and may be secured thereby to the body portion 10, by screws or the like 18.

Extending transversely of the lower portion of the body 10, there is a block 19, and it is on this block 19, that the legs 13 are pivotally mounted as indicated at 20. As illustrated in Figure 3, each of the legs 13 is cut out as at 21, and each has an extension 22 which projects to the upper end of the body portion 10, and each extension is spaced with respect to the back member 14. Carried by the upper end of the back member 14 there is a block 23, located in the space between the projections 22 of the legs, and the back member 14, and arranged upon the front face of the block 23, there are two stops preferably in the form of pins 24 which function to limit the movement of the legs about their pivotal point 20 in one direction. The upper ends of the extensions 22 are normally maintained in engagement with the stops 24 by means of a spring 25 herein illustrated as of the bowed type, secured as at 26 to the block 19 and having its free ends engaging the legs 13 as at 27. By this construction, pressure applied to the lower ends of the legs 13, to move them in the direction of each other, places the spring 25 under tension, as the legs are rocked about their pivotal points to move the upper ends of the extensions 22 outwardly in Figure 4. Relief of pressure upon the legs 13 causes the legs to be moved in the opposite direction under the influence of the spring 25, moving the upper ends of the extensions 30 inwardly in Figure 4 into engagement with the stops 24 thus which serve to normally position the legs as illustrated in Figure 4. A plate 28, is secured as at 29 to the under side of the neck and shoulder portion 17, and this plate has downwardly extended ends 30 which serve as stops for limiting the outward movement of the upper ends of the extensions 22 which engage these stops when the lower ends of the legs are moved towards each other.

Secured as at 31 to the under side of the block 23, there is a plate 32, and the ends of said plate 32 project beyond the body portion 100

of the doll as at 33. The arms 12 are pivotally mounted as at 34 upon the ends 33 of the plate 32 in a manner which permits of their swinging in a horizontal plane, to a position where the hands 35 of the arms will engage each other in front of the doll. Each of the hands 35 is formed with an inwardly disposed flat face 36, and when the hands are brought together in front of the doll contact of these faces produces a noise in imitation of that produced by a person clapping the hands.

The arms 12 are moved about their pivotal point by movement of the legs 13 about their pivotal points in the manner heretofore described, and to effect this movement of the arms, they are connected to the legs by links 37 and 38. By reference to Figure 4, it will be noted that viewing the doll from the front, the link 37 connects the right arm with the left leg, and the link 38 connects the left arm with the right leg thereof.

From the foregoing, it will be apparent that when the lower ends of the legs are moved towards each other, the arms will be moved to bring the hands together, and the spring 25 will be placed under tension. Immediately pressure upon the legs is relieved, the spring 25 acts to return the legs and arms to initial position. Thus it will be apparent that by a series of movements of the legs the toy may be made to bring the hand portions 35 of the arms 12 together, and thus imitate a child or person performing the act of clapping hands.

While the invention has been herein illustrated in a preferred form, it is to be understood that it is not to be limited to the construction herein shown, but may be embodied in other forms which fall within the scope of the appended claims.

Having thus described the invention, what is claimed as new and desired to secure by U. S. Letters Patent, is:

1. In a figure toy, a body portion, rigid legs pivotally mounted on the body portion, arms pivotally mounted on the body portion and adapted for movement toward and away from each other in a horizontal plane, means for moving said arms about their pivotal points in one direction upon application of pressure to the lower ends of the legs, and means for automatically operating said legs and arms in the opposite direction upon relieving the pressure upon the lower ends of the legs.

2. In a figure toy, a body portion, rigid legs pivotally mounted on the body portion, arms pivotally mounted on the body portion and adapted for movement toward and away from each other, means for moving said arms about their pivotal points in one direction upon application of pressure to the lower ends of the legs, and means for operating said legs and arms in the opposite direction upon

relieving the pressure upon the lower end of the legs, said last mentioned means comprising a compression spring interposed between the leg members.

3. In a figure toy, a body portion, legs pivotally mounted on the body portion, arms pivotally mounted on the body portion and adapted for movement toward and away from each other, means for moving said arms about their pivotal points in one direction upon application of pressure to the lower ends of the legs, and means for operating said legs and arms in the opposite direction upon relieving the pressure upon the lower ends of the legs, said last mentioned means comprising a bowed spring mounted on the body portion and having its free ends engaging the leg members of the doll.

In testimony whereof I affix my signature.

WILLIAM P. BOSTWICK.
